United States Patent Office

Des. 184,260
Patented Jan. 13, 1959

184,260

TABLE TOP

John J. Lubberts and Lambert J. Mulder, Grand Rapids,
Mich., assignors to Tomlinson of High Point, High
Point, N. C., a corporation of North Carolina

Application April 2, 1957, Serial No. 45,533

Term of patent 14 years

(Cl. D33—14)

In the drawing the dotted lines are present only for illustrative purposes.

We claim:

The ornamental design for a table top, substantially as shown and described.
